UNITED STATES PATENT OFFICE.

CARL A. PORATH, OF KOKOMO, INDIANA, ASSIGNOR TO KOKOMO STEEL AND WIRE COMPANY, OF KOKOMO, INDIANA, A CORPORATION OF INDIANA.

FENCE-WEAVING LOOM.

1,426,007.

Specification of Letters Patent. Patented Aug. 15, 1922.

Application filed November 2, 1920. Serial No. 421,371.

To all whom it may concern:

Be it known that I, CARL A. PORATH, a citizen of the United States, residing at Kokomo, in the county of Howard and State 5 of Indiana, have invented new and useful Improvements in Fence-Weaving Looms, of which the following is a specification.

This invention relates to fence weaving machines or looms of that class wherein all 10 operations in forming the fence are mechanical, thereby producing an entirely automatic machine. One feature of the invention is the means for feeding an endless strand of wire lengthwise between a plurality of pairs of line wires, the feeding mechanism being arranged for so feeding the strand of wire that pickets of different lengths will be produced, said machine also having automatically operated parts for 15 making various crimps or curvatures in the pickets, and for positioning the pickets so that the parts thereof will be properly interwoven with the line wires of the fence, the pickets being partially woven into position 20 before they are cut into lengths.

A further feature of the invention is the provision of twistors which are split or formed into companion parts, said parts being so arranged that they will separate the 25 plurality of parts of line wires for the passage of the pickets when the parts of the twistors are separated, means being provided for automatically operating the sections of the twistors as a single one-piece twister when the parts of the twistors are 30 brought together.

A further feature of the invention is the provision of timing means in connection with parts of the machine for regulating the 35 feeding mechanism for the strand of picket forming wire whereby longer or shorter pickets may be formed, additional means being provided for omitting the feed of the picket forming wire at intervals.

A further feature of the invention is the provision of means for operating the twisting devices, said operating means having an interrupted movement, said movements being so timed that pickets may be entered between the line wires at the end of the movement of the twisting mechanism and certain of the pickets incorporated between the line wires during the interrupted period in the operation of the twisting mechanism, said twister operating parts having

means for reversing the twists at the completion of a full stroke of the twister operating device in one direction, whereby the line wires will be twisted a predetermined distance in one direction, and then twisted 60 in the opposite direction substantially the same distance thereby maintaining the line wires in proper condition to pass through the twistors and receive the pickets.

A further feature of the invention is the provision of means for automatically separating and bringing together the sections of the twister mechanism, these operations being timed to occur between the strokes of the twister operating mechanism. 70

A further feature of the invention is the provision of means for uniformly feeding and holding the line wires under tension, whereby the twists formed in the line wire will be uniform throughout the length of the 75 fence structure.

A further feature of the invention is the provision of automatically operated means for forming bends in the pickets, and for positioning the bent portions to be interwoven with the line wires, automatic means being provided for intermittently raising and lowering the picket bending means, and for imparting movement to said bending mechanism when in operative or inoperative 80 positions.

A further feature of the invention is the provision of means for moving the line wires and the woven part of the fence structure lengthwise for forming uniform 90 spaces between the pickets, means also being provided for forming the woven fence into a bundle or roll, the operation of all these various parts being performed automatically and in timed relation with each other. 95

Other objects and advantages will be hereinafter more fully set forth and pointed out in the accompanying specification.

In the accompanying drawings which are made a part of this application, 100

Figure 1 is a top plan view of the machine,

Figure 2 is an end elevation of the machine showing the twisting mechanism completing a stroke in one direction,

Figure 2^a is an enlarged end elevation of the arrangement and driving means for certain of the wire twisting mechanism,

Figure 3 is a view similar to Figure 2 showing the twistors in separated position and the operating mechanism for the twist- 110

ers in position to begin a reverse movement of the twisters,

Figure 4 is a side elevation of the machine showing the tensioning means for the line wires attached thereto,

Figure 5 is an elevation of the opposite side of the machine from that shown in Figure 4,

Figure 6 is an enlarged detail sectional view as seen on line 6-6 Figure 1,

Figure 7 is a detail sectional view as seen on line 7-7 Figure 1,

Figure 8 is a detail sectional view through one of the twisters showing the manner of applying and operating the tensioning means for the line wires,

Figure 8^a is a sectional view as seen on line 8-8 Figure 8,

Figure 9 is a front elevation of the mechanism shown in Figure 8,

Figure 10 is a top plan view of the driving mechanism for the various elements of the machine,

Figure 11 is a sectional view as seen on line 11-11 Figure 10,

Figure 12 is a sectional view as seen on line 12-12 Figures 1 and 10,

Figure 13 is a sectional view as seen on line 13-13 Figure 12,

Figure 14 is an elevation of the wire crimping mechanism as seen from line 14-14 Figure 12,

Figure 15 is an enlarged sectional view as seen on line 15-15 Figure 1,

Figure 16 is a similar view showing parts in a different position,

Figure 17 is a sectional view as seen on line 17-17 Figure 1,

Figure 18 is a similar view to Figure 17 with parts in a different position,

Figure 19 is a view similar to Figures 17 and 18 with the parts in a still different position,

Figure 19^a is a detail sectional view as seen on line 19-19 Figure 19,

Figure 20 is a detail sectional view as seen on line 20-20 Figure 6,

Figure 21 is a detail sectional view as seen on line 21-21 Figure 6,

Figure 22 is a detail sectional view on an enlarged scale as seen on line 22-22 Figure 6,

Figure 23 is a sectional view on an enlarged scale as seen on line 23-23 Figure 6,

Figure 24 is a detail top plan view of one of the picket bending heads,

Figure 25 is a detail sectional view as seen on line 25-25 Figure 24,

Figure 26 is a detail elevation of one of the picket bending heads showing the means for retaining certain pickets in operative position thereon,

Figure 27 is a plan view of a section of the fence showing the position of the picket

bending heads during one step in the bending operation,

Figure 28 is a similar view showing the next step in the bending operation,

Figure 29 is a detail sectional view of one of the picket bending heads showing its position when engaging the picket to bend the same,

Figure 30 shows an additional step in the bending operation,

Figure 31 is the position of the parts of the picket benders at the end of their cycle, and

Figure 32 is an end elevation of a section of the fence as seen from line 32-32 Figure 27.

Referring to the drawings in which similar reference numerals designate corresponding parts throughout the several views, 1 indicates a frame (see Figs. 1, 2 and 3) which may be constructed in any preferred manner and having end members and a cross connecting member 3, these parts being preferably formed of metal. Mounted upon the connecting member 3 at one end of the frame (see Figs. 3, 15 and 17) is a vertically movable bar 4 in the under face of which are formed a plurality of semi-circular recesses 5 in which are seated the upper halves 6 of line wire twisters, the lower halves 7 of said twisters being seated in semi-circular recesses 8 in the cross connecting member 3, said members 6 and 7, when placed together, being preferably circular in cross section. The upper and lower halves 6 and 7 of the twisters are provided with longitudinally extending bores 9 and 10 through which are extended the line wires 11 and 12, respectively, of the fence structure. The peripheries of the sections 6 and 7 are provided adjacent their ends with horizontally disposed outwardly extending flanges 13 and 14 with which engage the inwardly extending flanges of plates 15 and 16 attached respectively to the bar 4 and connecting member 3. The plates and the interlocking flanges serve to hold the two parts of the twisters in rotating position and prevent the same from dropping out of their recesses when the upper and lower sections 6 and 7 are moved apart.

The sections 6 and 7 forming the twisters are provided with gears 17 which mesh with driving gears 18 carried by horizontally disposed shafts 19, the outer ends of said shaft having pinions 20 thereon which mesh with the teeth 21 of a rack 22 (see Fig. 2), said rack preferably resting above said pinions and traveling transversely of the trend of the shafts 19. The rack bar 22 is moved longitudinally in opposite directions by means of levers 23 and 24 at opposite ends of the connecting member 3, the lower ends of the levers 23 and 24 being pivoted to blocks 25 and 26, which are in turn attached to the end members 2. The upper ends of the le-

vers 23 and 24 project a distance above the rack bar 22 and are provided with latches 27 and 28 respectively, which are adapted to enter the notches 29 and 30 arranged in series at the opposite ends of the rack bar 22, the latches 27 and 28 projecting inwardly towards the twisters and having their free ends rounded so that they will readily enter the notches or slide thereover when one or 10 the other of the levers is running idle. There are preferably two notches for co-operation with each of the latches, so that the rack will be given intermittent movement lengthwise in making a complete twist in the wires. The 15 levers 23 and 24 are rocked back and forth on their pivots by pivoting to the levers between their ends links 31 and 32 respectively, the opposite ends of said links being pivoted to heads 33 and 34, and eccentrically 20 to the axes of said heads, and as the heads are rotated the levers will be swung back and forth and the movement thereof be positive and even with no lost motion. This action will provide a variable speed for the 25 rack as it will give a slower movement to the rack at the beginning and end of its strokes. As it requires two or more actions of the levers to move the rack bar 22 its full length in either direction it is necessary to 30 provide means for elevating one of the latches while the other latch is operating the rack bar, and to this end a plate 35 (see Figs. 1 and 2) is slidably mounted against one face of the rack bar 22, said plate having 35 notches 36 therein, the notches at one end of the plate registering with the notches at the same end of the rack bar, so that the co-operating latch may enter the notches in the rack bar while the notches in the opposite 40 end of the plate are so positioned that they will be out of registration with the respective notches in that end of the rack bar, consequently the latch co-operating therewith will slide over the upper face of the rack bar and 45 be inoperative. The plate 35 is moved lengthwise automatically for shifting the notches at one end of the plate into registration with one set of the notches in the rack bar, and the notches at the opposite end of 50 the plate out of registration with the notches at the opposite end of the rack bar by means of arms 37 and 38 (see Figs. 2 and 3) said arms being pivoted between their ends to standards 39 and 40 respectively, which are 55 carried by parts of the frame 1. The arms 37 and 38 are normally held in vertical position by means of springs 41 and 42 which are attached at one end to the lower ends of the arms 37 and 38, and their opposite 60 ends to parts of the frame 1. The upper ends of the arms 37 and 38 extend into the path of a pin 43 carried by the plate 35 and projecting through a slot 44 is a guard plate 45, the pin being so positioned that as the 65 rack bar in making its last intermittent

movement in one direction the pin will be forced against the upper end of one of the arms and said arm moved laterally and outwardly, thereby tensioning the spring attached to said particular arm. As soon, 70 therefore, as the lever, which has just operated the rack bar, is moved outwardly a sufficient distance to disengage the latch from the rack bar, the tension of the spring on the arm which has been moved laterally 75 will force the plate 35 in the opposite direction, and consequently move the notches in the plate which has just been in registration with the notches in the end of the rack last receiving action from one of the latches and 80 registering the notches in the opposite end of the plate and rack bar. The latch co-operating with the notches last brought into registration enters said notches and intermittently moves the rack bar in the opposite 85 direction, consequently reversing the twisting action of the twisters.

The heads 33 and 34 are attached to shafts 46 and 47 (see Figs. 1, 5 and 6), which lie in a horizontal plane and extend through 90 bearings on parts of the end members 2, said shafts having on their ends opposite the heads 33 and 34, bevel gears 48 and 49 which mesh with bevel bears 50 and 51 respectively, on a shaft 52, and from which 95 the shafts 46 and 47 and parts attached thereto are operated.

In order to positively raise and lower the bar 4 and the parts of the twisting apparatus engaged thereby, so as to separate the 100 two sections of the twisters, as best shown in Figure 3 of the drawings, cams 53 and 54 are mounted upon the shafts 46 and 47 respectively, said cams when moved to position above the shafts 46 and 47 engaging 105 rollers 55 and 56 at the ends of the vertically movable bar 4, and with rollers 57 and 58 below the shafts 46 and 47 when the cam is moved to position below the shafts 46 and 47, the upward swinging movement 110 of the cams 53 and 54, elevating the bar 4 and parts carried thereby and causing the bar 4 to descend when the cams move downwardly to position below the shafts to which they are attached.

The shaft 52 is mounted in bearings 59 on the frame 1 (see Figs. 1, 6 and 10), and has one of its ends projecting through bearings in a sub-frame 60, said shaft 52 having a gear 61 fixed thereon (see Figs. 1, 120 10 and 11), which meshes with the teeth 62 of an intermittent gear 63, the shaft 52 and gear 61 having a Geneva stop mechanism 64 (see Fig. 11), in co-operation with the gear 63 to hold the gear 61 and shaft 52 against 125 rotation when the teeth 62 are out of mesh with the gear 61, thereby giving intermittent operation to the twister operating mechanism. The intermittent gear 63 is mounted upon a shaft 65 and said shaft 65 is driven 130

from any suitable source of power applied to a shaft 66, said shaft 66 having a pinion 67 thereon which meshes with a driven gear 68 on the shaft 65.

5 The present form of fence is built up of pickets of different lengths, although it will be understood that the length and formation of the pickets may be readily varied as occasion may require, the wire forming 10 the pickets being taken from a bale or roll of wire and cut into the proper lengths to form the pickets, the same operation positioning the pickets between the line wires of the fence. In accomplishing this result 15 (see Figs. 2, 10, 11 and 12), a single strand of wire 69 is entered between the feed rollers 70 which are preferably arranged in pairs, one above the other, said feed rollers being mounted upon shafts 71, the inner 20 ends of said shafts having intermeshing driven gears 72 attached thereto, and the lower shaft having a sprocket 73 (see Fig. 18), for engagement with a sprocket chain 74 and by means of which the feed rollers 25 70 are positively rotated.

After the wire passes through the feed rollers 70 it enters between a pair of crimping rolls 75 (see Figs. 2 and 14), which are mounted upon shafts 76, and these rolls 30 are positively driven by attaching gears 77 to the inner ends of the shafts 76. The inner end of the lower shaft 76 is positively driven by attaching thereto a bevel pinion 78 (see Fig. 10) with which meshes a bevel gear 79 which is in turn mounted upon a 35 shaft 80.

The sprocket chain 74 passes around a sprocket 81 on the lower shaft 76, and as said shaft 76 is positively driven the shafts 40 71 will be likewise positively driven, these parts being driven in unison.

The feed rollers 70 are intermittently rotated and are given a greater rotating movement when the longer picket is being fed in than when the shorter picket is being fed in, and to accomplish this result a gear 82 is attached to a shaft 83 (see Figs. 10 and 11), said gear 82 meshing with the teeth 62 of the intermittent gear 68, the gear 82 and shaft 83 likewise having a Geneva stop mechanism 84 for holding the gear and shaft against rotation at certain intervals. Mounted upon the shaft 83 is a sprocket wheel 85 around which passes a sprocket chain 86, said chain also extending around a sprocket 87 on a shaft 88 and by means of which said shaft is driven. One end of the shaft 88 has a gear 89 fixed thereto which meshes with a gear 90 on the shaft 80, and as 50 the bevel gear 79 engages and operates the bevel pinion 78 and parts connected therewith, said parts are driven from the shaft 88 and members connected therewith.

The sprocket wheel 85 is rotatably mounted upon the shaft 83, and said sprocket

wheel is driven by a ratchet 91 (see Figs. 10 and 12), which ratchet has a single tooth 92, and co-operating with said ratchet is a pawl 93 pivotally mounted to the outer end of an arm 94 fixed to the shaft 83, and so long as said pawl is in engagement with the tooth 92 the ratchet 91 and sprocket 85, and the parts co-operating therewith will be positively driven, the pawl being normally held in engagement with said tooth by means of a spring 95. As the sprocket chain 86 and parts connected therewith necessarily travel at a more or less high rate of speed at times, any back lash is prevented by means of a roller ratchet mechanism 86^a 80 (see Fig. 11), which co-operates with an idler sprocket 86^b which in turn engages the sprocket chain 86 between the sprockets 85 and 87.

As best shown in Figure 27 this machine 85 is arranged to form main pickets 96 and auxiliary pickets 97, the auxiliary pickets being shorter than the main pickets and are constructed substantially U-shaped, one arm of the picket 97 being positioned at one side 90 of one of the main pickets, and the other arm an equal distance at the opposite side of the main picket, and in view of making the pickets in this manner it is necessary to skip one picket in every four, consequently it is necessary to stop the feeding mechanism for the pickets during one-quarter of the cycle of operation of the picket feeding mechanism. This is accomplished by placing a cam 98 (see Figs. 10 and 12), 100 on a shaft 99, which cam at one portion of the revolution thereof strikes the free end of the pawl 93 and moves the opposite end thereof out of the path of the tooth 92 thereby permitting the arm 94 to continue its 105 revolution while the ratchet 91 and parts connected therewith remain idle during one complete revolution of the shaft 83 and arm 94, consequently the picket feeding mechanism remains idle and the feeding of one 110 picket is omitted. Before the arm 94 makes a complete revolution the cam 98 will have turned out of the path of the pawl 93, consequently the end of the pawl will again engage the tooth 92 and start the feeding 115 mechanism for the pickets.

In view of the fact that the pickets are made in different lengths means are provided for varying the duration of the operation of the picket feeding mechanism and 120 this is accomplished by attaching an arm 100 (see Figs. 10 and 12) to the hub of the sprocket wheel 87, said arm being preferably threaded onto the end of the hub of said sprocket, the free end of the arm having a pawl 101 pivoted thereto, one end of which co-operates with teeth 102 of a ratchet wheel 103, said ratchet wheel being fixed to one end of the shaft 88, and so long as the pawl is in engagement with the teeth of the 125 130

ratchet of the shaft 88 parts co-operating therewith will be rotated, the pawl 101 being normally held in engagement with the teeth 102 by means of a spring 104.

5 As it is necessary to shorten the feeding operation when the shorter pickets are being fed into the fence structure, a lever 105 is provided, one end of the lever being pivoted to parts of the sub-frame and the opposite 10 end thereof provided with a curved extension 106 for engagement with the outer end of the pawl 101, and by varying the curvature of this extension the length of the shorter picket 97 may be varied, the gears 15 89 and 90 being changed for operating these parts in conformity to the changed condition occasioned by the change in curvature of the part 106. In stopping the operation of the feeding mechanism during the formation 20 of the shorter picket the curved end of the lever 105 is moved upwardly so that the free end of the pawl 101 will engage the curved surface and will be released from the teeth of the ratchet 103 by attaching 25 a cam 107 to a shaft 108, said cam engaging a roller 109 on the lever 105, and as soon as the pawl engages the curved surface of the lever the pawl will be disengaged from the ratchet teeth thereby permitting 30 the ratchet wheel 103 and shaft 88 to remain idle until such time as the arm 100 has rotated sufficiently to release the end of the pawl 101 from the curved surface of the lever 105 when the pawl will again engage 35 the ratchet 103 and start up the picket feeding mechanism.

As previously stated, the degree of curvature of the extension 106 determines the number of teeth that the pawl 101 will 40 skip during the time that the pawl is engaged by the curved extension. The cam 107 is likewise so arranged that it will operate the lever 105 at every fourth revolution of the arm 100, as the shorter picket is 45 formed at every fourth revolution of the arm 100. The shaft 99 has a gear 110 attached thereto (see Figs. 1 and 12) while the shaft 108 has a similar gear 111 attached thereto, which gears both mesh with a pinion 112 on the shaft 65, both gears being 50 driven from said shaft. The picket feed rollers 70 are vertically adjustable to adapt them for the reception of wires of greater or less diameter, these adjustments being controlled by adjusting screws 70^a (see Fig. 1), and the crimping rollers 75 are likewise adjusted by adjusting screws 75^a. The pickets, as they are fed between the line wires 11 and 12, pass through guides 113 (see 55 Figs. 1, 6 and 21), which are attached to a bar 114 extending transversely of the line wires and adjacent the inner ends of the twistlers for the line wires, the guides being elevated above the path of the line 60 wires while the twisting operation is being performed, and lowered for receiving the pickets as they are fed between the sets of line wires, the ends of the bar 114 being attached to vertically extending rods 115 the lower ends of said rods being pivoted 70 to one end of rocker arms 116, the opposite ends of said rocker arms co-operating with cams 117 on the shaft 65. The bar 114 also carries a presser-foot 118 which engages the curved end of the picket 97 75 when the bar 114 is lowered and depresses said curved end so that the main picket 96 being fed between the line wires will pass over the curved end of the shorter picket. The strand of wire 69 is cut into lengths 80 to form pickets by passing the strand of wire through a cutter-head and guide 119 (see Figs. 6 and 20), a knife 120 being pivoted to a bracket 121, the outer end of the knife being pivoted to an arm 122 of 85 an eccentric 123, said eccentric being attached to the shaft 52 and operated thereby.

As best shown in Figure 2^a the line wires adjacent the top portion of the fence are 90 formed relatively close together and in order to accommodate the twistlers, and keep them in the same horizontal plane, one of the twistlers is geared and operated from the other twister by gears 17^a adjacent the 95 outer ends of the sections 6 and 7, said twistlers lying side by side and in close proximity to each other. By arranging the twistlers in this manner and omitting the line wires from the twister meshing with 100 the driving gear for the twistlers the machine may be adapted for weaving a fence of extreme height without changing any of the parts of the machine. In constructing that form of fence shown in Figure 27 105 the ends of the pickets 96 forming the top portion of the fence are bent substantially semi-circular and the free ends of the top portion of the pickets are woven into the line wires, and a part thereof extended 110 along the vertical portion of one of the adjacent pickets, and to accomplish this result a bending head 124 is provided (see Figs. 1, 15, 16 and 24), said head having stationary formers 125 on the upper surface 115 thereof which form the curvature of the bent end of the picket, said end being carried around said formers by a bending pin 126. This pin is mounted on an arm 127 which is rotatable and carries the pin in a 120 circular path around the head, the arm and pin being driven by a bevel gear 128 which meshes with a bevel pinion 129 on a horizontally disposed shaft 130, said shaft being rotatably mounted in a bracket 131 125 which bracket also carries the bending head and parts associated therewith. The shaft 130 is intermittently rotated by mounting an intermittent gear 132 on a shaft 133, said intermittent gear meshing with a bevel pin- 130

ion 134 on the shaft 130, and in order to hold the shaft 130 and parts associated therewith from rotating when the teeth of the intermittent gear are out of mesh with the pinion 134 one portion of the projecting end of the shaft 130 is provided with a flattened face 135 which engages the flat face of a segmental plate 136 on the gear 132. As it is necessary to raise or lower the head 10 during the operation of bending the end of the pickets the bracket 131 is pivotally mounted on the shaft 133 and the head is moved upwardly by means of a cam 137 mounted upon a sleeve 138, said sleeve being positioned around the shaft 52, the cam 137 striking a roller 139 mounted on the bracket 131. The head 124 is raised when the bending pin 126 starts to rotate thereby elevating the pin 126 sufficiently to engage one of 20 the pickets and also to position the formers in the path of the bending end of the picket, but as soon as the pin has made one-half revolution and completes its bending operation the cam 137 has turned beyond the roller 139 and permits the head to again descend. As there are always two pickets 96 between the line wires, the ends of which are not bent, it is necessary to elevate the picket which is not being bent in order to 30 permit the end of the bending picket and the bending pin to pass below the same. To accomplish this result a block 140 (see Figs. 24, 25 and 26) is positioned on the head 124 between the formers 125 and the picket 35 which is not to be bent will encounter said block and be moved upwardly as the head 124 is elevated, consequently the pin 126 and the bending end of the other picket will pass below the elevated picket. The teeth 40 on the intermittent gear 132 are so arranged that the bending pin 126 will remain stationary at the completion of the operation of bending the end of one picket and will hold said bent end until such time as an additional picket has been fed between the line wires and the twisting operation started, a sufficient amount of twist being made to hold the bent end of the picket in position after being released from the pin. At 45 this time the cam 137 passes from below the roller 139 when the bracket and parts carried thereby will descend and move the bending head and parts thereon out of the path of the pickets. The intermittent gear 132 will have made substantially one-half of a revolution by this time and will again set up rotation of the gear 128 and move the bending pin to its initial starting point and ready for bending another picket. 50 The sleeve 138 is driven from the shaft 65 by placing a sprocket wheel 141 on said sleeve (see Fig. 7), and a sprocket 142 on the shaft 65, a sprocket chain 143 connecting said sprockets. The shaft 133 is driven 60 from the shaft 65 by attaching an intermit- tent gear 144 to said shaft 65, (see Fig. 5), and in order to rapidly operate the bending pin 126 the teeth 145 of the gear 144 mesh with an idle gear 146 and said idle gear in turn meshes with a gear 147 mounted upon a stub-shaft 148, the gear 147 having a sprocket gear 149 attached thereto around which passes a sprocket chain 150, said chain also passing around a sprocket 151 on the outer end of the shaft 133. This manner of gearing the bending pin, and parts operating the same, to the shaft 65 causes said pin to move rapidly during its bending operation. 70

In forming the bend in the picket 97 two separate and distinct operations are required, the first bend being made by a bending pin 152 (see Fig. 19), which is carried on a revolving shaft 153, said shaft being mounted in a bearing 154 on parts of the frame 1, the shaft being rotated by a rack 155 slidably mounted, in parts of the frame 1 which co-operates with a pinion 156 on the lower end of the shaft 153. The rack 151 is moved in one direction for 80 swinging the pin 152 for bending the picket 97 from a cam 157, said cam having a recess 158 in its peripheral edge into which enters a roller 159 carried by the rack 155. When the pin 152 is swung outwardly to receive the picket 97, as it is entered between the line wires, the picket passes between the pin 152 and the face of the frame member. The pin 152 normally rests adjacent the face of the frame member and is swung outwardly 90 when the roller 159 registers with the slot 158 through the medium of a spring 160. Co-operating with the bending pin 152 is an anvil 161 (see Fig. 18), carried at the upper end of the thrust bar 162, said bar 95 passing through a bearing 163 on parts of the frame 1, the thrust bar 162 and anvil carried thereby being vertically movable through said bearing so that the anvil may be raised into the path of the picket while 100 receiving its first bending operation and is moved downwardly and out of the path of the bending portion of the picket during the second bending operation. 105

Thrust bar 162 is moved vertically 115 through the medium of a rocker arm 164 which is pivoted at its center and has an elongated slot 165 at one end for engagement with the wrist pin 166 on the thrust bar, and has a roller 167 at its opposite end for engagement with a cam 168 mounted upon a sleeve 169, said sleeve being also rotatably mounted around the shaft 52 similar to the sleeve 138, and if preferred the two sleeves may be connected at their meeting ends by a 120 boss 170. The cam 168 is so positioned with respect to the recess 158 that as the roller 159 moves into engagement with one of the inclined end walls of said recess the cam 168 will engage the roller 167 and move the 125 130

thrust bar, and anvil carried thereby, upwardly and into the path of the bending portion of the picket 97, the face of the anvil being curved so as to form the proper curvature in the picket. This operation leaves the bending end of the picket extending at right angles to the natural position of the picket and in order to accommodate the swinging end of said picket the meeting faces of the connecting member 3 and the vertically movable bar 4 are provided with elongated transversely extending recesses (see Figs. 6, 22 and 23), which when the bar is in engagement with the member 3, form a slot 171 in which the end of the picket being bent rests during the interval that one of the pickets 96 is being positioned and twisted between the line wires 11 and 12.

The second bending operation on the picket 96 is performed by a bending head 172 and a bending pin 173 cooperating therewith (see Figs. 1, 17, 18 and 19), the head 172 having formers 174 thereon, one of which engages the bend in the picket and the other is positioned to form or complete the last portion of the bending operation. The pin 173 is attached to a bevel gear 175 which is rotatably mounted on a bracket 176, which bracket carries the head 172. Meshing with the gear 175 is a bevel pinion 177 mounted on the end of a shaft 178, said shaft extending through a sleeve 179 of the bracket 176, the outer end of the shaft 178 having a bevel pinion 180 which co-operates with the teeth 181 of a segmental gear 182, the shaft 178 having a flat face 135^a for engagement with the plate 136^a to hold the shaft and parts operated thereby stationary when the teeth 181 are out of mesh with the gear 180 (see Fig. 19^a). The gear 181 is mounted upon a shaft 183 (see Fig. 7), which shaft is similar to the shaft 133 and is driven from the shaft 65 through the medium of a sprocket chain 184 and sprocket gears 185 and 186 on the shafts 65 and 183 respectively. The shafts 133 and 183 are in alignment with each other and their meeting ends are connected by a sleeve 187.

It is also necessary to raise and lower the head 172 and parts co-operating therewith so as to permit the bending wire to pass below the other line wires, consequently the bracket 176 is pivotally mounted to the shaft 183 and the end of the bracket carrying the head 172 is elevated by means of a cam 188 mounted upon the sleeve 169, a roller 189 being attached to the bracket 176 with which the cam co-operates. To avoid buckling or bending of the picket 97 a guard 190 is attached to thrust bar 162 and is so spaced that the picket 97 will pass between the guard and anvil 161 and is raised and lowered with the thrust bar (see Fig. 18).

The sleeve 169 is driven from the shaft 108, said shaft having a sprocket 191 thereon

around which passes a sprocket chain 192, said sprocket chain also passing around a sprocket 193 on the sleeve 169.

The upper sections of the line wire twisters, when the bar 4 is in an elevated position, are held against rotating movement by brake members 194 (see Figs. 6 and 17), which project through sockets in a bar 195, the brake members being held in frictional engagement with the upper section of the twisters by means of springs 196, the pressure of the member 194 against the upper section of the twisters being sufficient to hold said sections against rotating movement while the lower sections of the twisters will be held against movement by the gears 18. The ends of the pickets 96 are held in position for engagement with the bending pin 126 by providing a guard 197 (see Figs. 1 and 26), one end of the guard being attached to parts of the frame of the machine while the opposite end thereof is curved upwardly and placed in position to engage with the ends of pickets 96, and to move the ends of the pickets downwardly so that they will lie in the path of the bending pin.

The woven fence fabric is wound on a reel 198, said reel having a friction clutch mechanism 199 which will compensate for the movement of the reel incident to the increased diameter of the roll of fence as it is wound onto the reel. The woven fabric in its travel from its weaving point to the reel passes over a spacing drum 200, said drum having flanges 201 thereon which pass between the pickets of the fence, said flanges having notches 202 therein for the reception of the line wires, and the flanges are so positioned that the woven fabric will be intermittently moved a prescribed distance lengthwise for properly spacing the pickets between the line wires. The drum 200 (see Fig. 5), is intermittently operated by attaching to the shaft 203 supporting the drum, a ratchet 204 with which co-operates a pawl 205 carried by a swinging lever 206, the drum being held against reverse rotation by means of a dog 207 co-operating with the ratchet 204. The lever 206 is rocked back and forth for operating the drum by attaching a pitman 208 to the lower end of the lever 206, the opposite end of said pitman being attached to a wrist pin 209 eccentrically mounted on a hub 210 attached to the shaft 52.

The opposite end of the shaft 203 from the ratchet 204 is provided with a sprocket wheel 211, and from which the reel 198 is driven, said reel having a sprocket 212 thereon, around which and sprocket 211 passes a sprocket chain 213, so that the reel will be operated to wind the woven fabric thereon co-incident to the operation of the drum for moving the woven fabric as the pickets are woven thereinto.

In order to hold the line wires 11 and 12 at proper tension to make them twist in a uniform manner (see Figs. 4, 8 and 9), said line wires are passed over grooved wheels 214 which are carried at the upper ends of pivoted arms 215, the lower ends of said arms having springs 216 attached thereto, the opposite ends of the springs being attached to parts of the frame 1, these springs being employed for taking up any slack in the line wire. In addition to employing the tension of springs 216 for holding the line wire taut the wire is passed between rollers 217 and 218, the roller 217 being mounted upon a fixed shaft while the roller 218 is eccentrically mounted and has a weight 219 attached thereto for gripping the roller 218 against the wire inserted between it and the roller 217. The line wires are given a positive feed by attaching to the shaft 220, upon which the rollers 217 are mounted, a sprocket wheel 221 around which passes a sprocket chain 222, said chain also extending around a sprocket 223 on a shaft 224, the shaft 220 and sprocket 223 mounted thereon being driven through a train of gears 225 from the shaft 65. The rollers 217 and 218 are connected to intermeshing gears 226 and 227 respectively, the gear 226 being attached to the shaft 220, and possibly driven thereby. The train of gears 225 are so arranged that they may be interchanged for increasing or decreasing the feed of the wire incident to forming different grades of fence.

In operation, supposing the parts to be in the position shown in Figs. 3 and 11, the line wires 11 and 12 are threaded through the tensioning mechanism and through the respective bores in the sections 6 and 7 of the twisters and are then carried across the drum 200 and connected with the reel 198. One end of the picket forming wire 69 is entered between the feed rollers 70 and moved into engagement with the crimping rolls 75, and the crimping rolls then manually operated by applying any suitable form of implement to the squared end of the upper shaft 76 until the end of the wire reaches the wire cutter or is in position to feed a picket when the feeding and crimping mechanism is set in motion.

Power is then applied to the pulley 228 and the shaft 66 driven, and through the gears 67 and 68 the intermittent gear, 63 will be rotated. This starts the driving of the gear 82 and parts connected therewith, consequently setting up operation of the wire feeding and crimping mechanism and introducing a picket between the line wires.

If a long picket is being fed into the machine the bending head 124 is set in motion and owing to the rapidity with which the bending pin 126 is operated, the outer end

of one of the long pickets is bent into proper shape previous to the completion of the longitudinal movement of the picket being fed into the machine, the pin 126 being stopped at such a point as to hold the end of the bent portion of the picket so that the end of the feeding picket will pass by the end of the bent picket without catching on the pin 126. As soon as the gear 63 has rotated a sufficient distance to again bring the teeth 62 into engagement with the gear 61, the shaft 52 will be rotated, this action operating the cams 53 and 54 for lowering the top bar 4. As soon as the bar 4 has been lowered to bring the two sections of the twisters together one of the latches, in this instance the latch 27 as shown in Figure 3, will enter one of the notches 29 and move the bar 22 lengthwise, the movement of said bar being such that the line wires will be given a full twist and another half twist, the continued rotation of the cams 53 and 54 again raising the bar 4 and separating the sections of the twisters and simultaneously with the separation of the twister sections the drum 200 will be operated to move the woven fabric and line wires a sufficient distance to space the line wires for receiving the next succeeding picket, in this instance the shorter picket. While the line wires are still separated the upper end of the shorter picket is bent at right angles to the lower portion thereof, as shown in Figure 28 of the drawings, the anvil 161 having been elevated by the cam 168 and the bending pin 152 having been swung to its outward position by the rack bar 155 co-operating with the recess 158, the inward swinging movement of the pin 152 positioning the top end of the short picket parallel with the line wires and in registration with the slot 171 between the members 3 and 4. The bar 4 is then again lowered when the latch 27 will engage the outermost notch 29 in the bar 22 and finish the stroke of the bar 22, thereby completing the twisting operation which normally comprises three complete twists of the line wires, each stroke of the bar making substantially one and one-half turn or twist in the line wires.

The bar 4 is then again raised and the drum 200 again operated for moving the woven fabric for spacing the same to receive the next picket 96, or one of the longer pickets. The teeth 62 are now again in position for leaving the gear 61 and re-engaging the gear 82, and when so engaged the longer picket is fed between the line wires. Co-incident to the starting up of the picket feeding and crimping mechanism the cam 117 will operate the rocker arms 116 for lowering the guides 113 to receive the pickets and when the picket feeding operation last described is being performed the foot 118 descends and forces the right-angular bent 130

portion of the shorter picket 97 downwardly thereby permitting the feeding picket to pass over the bent portion of the shorter picket.

5 The bar 4 is again lowered and the rack 22 again operated for twisting the line wires, but in this instance, the arm 38 having engaged the pin 43 at the last longitudinal stroke of the rack bar and moved 10 the plate 35 longitudinally to bring the notches therein in registration with the notches 30 in the rack bar, the latch 28 will engage the innermost recess 30 and reverse the rotation of the twisting members and reverse the twist in the line wires. 15 When the lever 24 has been operated to impart the first longitudinal movement of the rack bar 22, the bar 4 is elevated to again separate the line wires, but as no 20 picket is to be fed between the line wires at this time the picket feeding mechanism will have reached the position shown in Figure 12 of the drawings, wherein the cam 99 has operated the pawl 93 and released the same 25 from the tooth 92, whereupon the arm 94 and pawl carried thereby, will rotate around the ratchet 91, the picket feeding mechanism remaining idle. During this interim, however, the bending head 172 will have 30 been operated to position the former 174 in position to engage the angularly extending end of the picket 97 and the pin 173 will have been rotated so that it will engage the angularly extending portion of 35 the picket 97 and bend the same around the former 174 and dispose the angular portion of the picket into alignment with the other portion of the picket. The bar 4 is then again lowered and the twisting 40 operation again set up, it being understood of course, that the drum 200 is operated for spacing the fence structure previous to the feeding in of each succeeding picket.

As the pickets are preferably crimped 45 they are not severed into lengths until after the twisting operation has started, thereby holding the bends of the pickets in their proper position for interweaving the pickets with the line wires.

50 When the shorter picket is fed between the line wires the cam 107 will have elevated the extension 106 of the lever 105, so that the pawl 101 will be disengaged from the teeth 102 of the ratchet wheel 103, just previous to the beginning of the feeding operation for the short picket, consequently the feeding mechanism for the picket will remain stationary until the arm 100 will have moved a sufficient distance to disengage the 55 end of the pawl 101 from the curved surface of the extension 106, whereupon the end of the pawl will be moved into engagement with the teeth of the ratchet 103 and the feeding operation start from this point. 60 65 As a part of the revolution of the arm 100

has been completed before the operation of the feeding mechanism is started the picket so formed by this feeding operation will be shorter than the other pickets.

As shown in Figure 27 of the drawings 70 the parts are positioned as when the shorter picket is being fed into the machine. In Figure 28 of the drawings the shorter picket 97 is shown as partially bent into position, the upper end portion thereof being at right angles to the lower portion. Figure 30 shows the position of parts when the bending of the short picket is completed, and Figure 31 shows the position of the parts at the completion of the cycle of 75 80 forming the shorter picket.

In view of the foregoing description it will be seen that the operation of forming and bending the pickets and interweaving the same with the line wires of the fence structure is accomplished entirely mechanically and automatically as no manual operations are required in performing any of the various operations. It will further be seen that by forming the twisters in 85 companion parts and separating them to receive the pickets when they are fed into the machine, the machine can be very compactly built as it is not necessary to move any of the parts of the machine laterally when the 90 upper end of the shorter picket is being bent over and downwardly. It will likewise be seen that the machine may be readily adjusted for weaving the pickets into the line wires at varying distances apart, and 95 the contour of the bent portions may be readily changed without changing or effecting the operation of the machine.

It will likewise be seen that the weaving operation may be performed at various 105 speeds by properly timing the various co-operating parts of the feeding and twisting mechanism, together with the spacing drum, and by providing the tensioning means for the line wires the twists in said 110 line wires will be kept uniform throughout the length of the fence structure.

What I claim is:

1. In a fence weaving machine, sectional means for forming twists in the line wires 115 of a fence structure, means for feeding pickets between the line wires, and means for simultaneously lifting one section of each twisting device for separating the line wires for receiving the pickets.

2. In a fence weaving machine, sectional means for forming twists in the line wires of a fence structure, means for lifting one section of each twisting device for separating the line wires, and mechanically operated means for feeding pickets between 120 125 the line wires.

3. In a fence loom, means for feeding a strand of wire between line wires of a fence structure, means for cutting said line wire 130

- into lengths for forming pickets, rotating the woven fabric after the bending operation has been completed.
5. In a fence loom, means for feeding a strand of wire lengthwise and positioning the fed portion between line wires of a fence structure, means for severing the line wire in lengths for forming pickets, means for varying the length of said pickets, means for controlling the feed of said pickets, means for interweaving the pickets with the line wires, and means for moving the interwoven pickets and line wires intermittently for spacing the same for receiving an additional picket.
10. In a fence loom, means for feeding a strand of wire between pairs of line wires, means for severing the strand of wire into lengths for forming pickets, means for forming bends in portions of said pickets after the pickets are introduced between the line wires, and automatically operated means for forming the pickets in different lengths at stated intervals.
15. In a fence loom, means for feeding a strand of wire between pairs of line wires, means for severing the strand of wire for forming pickets, means for varying the length of said pickets, and means for omitting the feeding of the strand of wire at stated intervals during the operation of the machine.
20. In a fence loom, means for feeding a strand of wire to position between pairs of line wires, means for severing the strand of wire into lengths to form pickets after the pickets are positioned between the line wires, means for bending said pickets to form the pickets in different shapes, means for forming certain of said pickets of less length than the remainder of the pickets, and means for eliminating the feeding of a picket at certain intervals.
25. In a fence loom, means for feeding a strand of wire to position between pairs of line wires, means for severing the strand of wire into lengths to form pickets after the pickets are positioned between the line wires, means for bending said pickets to form the pickets in different shapes, means for forming certain of said pickets of less length than the remainder of the pickets, and means for eliminating the feeding of a picket at certain intervals.
30. In a fence loom, means for feeding a strand of wire to position between pairs of line wires, means for severing the strand of wire into lengths to form pickets after the pickets are positioned between the line wires, means for bending said pickets to form the pickets in different shapes, means for forming certain of said pickets of less length than the remainder of the pickets, and means for eliminating the feeding of a picket at certain intervals.
35. In a fence loom, means for feeding a strand of wire to position between pairs of line wires, means for severing the strand of wire into lengths to form pickets after the pickets are positioned between the line wires, means for bending said pickets to form the pickets in different shapes, means for forming certain of said pickets of less length than the remainder of the pickets, and means for eliminating the feeding of a picket at certain intervals.
40. In a fence loom, means for feeding a strand of wire to position between pairs of line wires, means for severing the strand of wire into lengths to form pickets after the pickets are positioned between the line wires, means for bending said pickets to form the pickets in different shapes, means for forming certain of said pickets of less length than the remainder of the pickets, and means for eliminating the feeding of a picket at certain intervals, all of said parts being driven from a single source of power.
45. In a fence loom, means for feeding a strand of wire lengthwise between pairs of line wires, means for cutting said strand of wire into lengths to form pickets, means for forming bends in said pickets after they are positioned between the line wires, automatically operated timed means for controlling the operation of said bending means, and means for intermittently raising and lowering the bending means whereby said bends may be formed and the bending mechanism removed from the path of
5. In a fence loom, means for feeding a strand of wire lengthwise and positioning the fed portion between line wires of a fence structure, means for severing the line wire in lengths for forming pickets, means for varying the length of said pickets, means for controlling the feed of said pickets, means for interweaving the pickets with the line wires, and means for moving the interwoven pickets and line wires intermittently for spacing the same for receiving an additional picket.
10. In a fence loom, means for feeding a strand of wire between pairs of line wires, twisters for said line wires formed in halves and having longitudinal bores through which the line wires extend, and means for lifting one of the halves of the twisters a distance above the other half for spacing the pairs of line wires to form a passage for the strand of wire, and means for severing the strand of wire for forming pickets.
15. In a fence loom, means for feeding a strand of wire between pairs of line wires, means for cutting said strand of wire into lengths for forming pickets, a twister for each pair of line wires, each twister being formed in halves and each half having a longitudinal bore through which one of the line wires passes, supporting means for the twister sections, means for intermittently rotating said twisters, and means for lifting one section of each twister vertically a distance above the other section for spacing the line wires to receive the pickets.
20. In a fence loom, means for feeding a strand of wire between pairs of line wires, means for severing said strand of wire in lengths for forming pickets, sectional twisters co-operating with said line wires for interweaving the pickets with the line wires, means for intermittently raising one section of each twister vertically away from the other section for separating the line wires, means for intermittently rotating said twisters, and means for reversing the movement of the twister operating means at predetermined intervals.
25. In a fence loom, means for forming twists in pairs of line wires, comprising twisters formed in sections, said sections having longitudinal bores through which the line wires pass, means for intermittently raising one section of each twister vertically away from the other section for separating the line wires and intermittently operated means for rotating said twisters.
30. In a fence loom, means for forming twists in pairs of line wires, comprising twisters formed in companion sections, said sections having longitudinal bores through which the line wires pass, means for rotating said twisters, means for raising verti-

cally one section of each twister for separating the companion twister sections for spacing the pairs of line wires apart, and means for intermittently rotating said twisters 5 when the companion sections are together.

15. In a fence loom, means for forming twists in pairs of line wires, comprising twist-
ers formed in companion sections, said sec-
tions being semi-circular in cross section, said
10 sections having longitudinal bores through
which the line wires pass, means for separating
said companion sections by intermittently
lifting one section of each twister for
spacing the line wires apart, means for rotat-
ably mounting the twisters, and means for
15 intermittently rotating the twisters when the
companion sections are brought together.

16. In a fence loom, means for forming twists in pairs of line wires, comprising
20 twist-
ers formed in companion sections, said sec-
tions being semi-circular in cross section, said
sections having longitudinal bores through
which the line wires pass, means for separating
said companion sections by inter-
mittently lifting one section of each twister
25 for spacing the line wires apart, means for rotatably mounting the twisters, means for
intermittently rotating the twisters when
the companion sections are brought together,
30 and means for holding the sections of the
twisters against rotation when in separated
position.

17. In a fence loom, means for feeding a
35 strand of wire between line wires to form
pickets, means for twisting the line wires
together between the pickets for interweav-
ing the pickets with the line wires, comprising
twisters formed in companion sections,
40 each section having a longitudinal bore
through which one of the line wires of each
pair extends, means for rotatably mounting
the twister sections, means for separating
the twister section for spacing the pairs
45 of line wires for the reception of the pickets,
means for intermittently rotating said
twister sections when in closed position, and
means for reversing the rotation of said
twisters at intervals.

18. In a fence loom, means for forming
50 twists in line wires, comprising companion
twisting members, a rack bar for rotating
said twister members, means for imparting
intermittent longitudinal movement to the
rack bar, means for separating the com-
55 panion twister sections between the longi-
tudinal strokes of the rack bar, means for
feeding a strand of picket forming wire be-
tween the line wires when the twister sec-
tions are separated, and means for automati-
60 cally and intermittently reversing the move-
ment of the rack bar.

19. In a fence loom, means for feeding a
picket forming wire between pairs of line
wires, twister members for twisting the line
65 wires for incorporating the pickets therein,

a longitudinally movable rack bar for oper-
ating the said twisters, said bar having a se-
ries of notches adjacent the opposite ends
thereof, pivotally mounted levers having
means thereon for engagement with said 70
notches for moving the rack bar lengthwise,
means for rocking the levers on their pivots
for intermittently operating the rack bar, a
plate associated with said rack bar having a
series of notches therein, one of which series 75
is adapted to register with the notches at one
end of the rack bar, and the notches in the
opposite end of the plate being out of regis-
tration with the notches in the opposite end
of the rack bar, and automatically operated 80
means for shifting said plate whereby the
different series of notches in the rack bar
will be brought into operation whereby the
movements of the rack bar will be reversed.

20. In a fence loom, means for feeding a 85
picket forming wire between pairs of line
wires, means associated with the line wires
for forming twists therein at points between
the pickets, a rack bar for rotating said
twisting means, said rack bar having a se-
90 ries of notches adjacent its ends, swinging
latches for cooperation with said notches,
pivotally mounted rocking levers carrying
said latches, means for swinging said levers
on their pivots, means for causing one of 95
said latches to run idle while the other latch
is moving the rack bar longitudinally, and
means for intermittently bringing the op-
posed latch into operative relation with their
respective notches for reversing the longi- 100
tudinal movement of the rack bar.

21. In a fence loom, means for feeding a
strand of wire between pairs of line wires,
means for severing said strand of wire into
lengths for forming pickets, means for vary- 105
ing the feed of the picket forming wire for
forming pickets of different lengths, means
for bending one end of the longer pickets for
interweaving said bent ends with the line
wires, means for holding certain of the 110
longer pickets out of the path of the extend-
ing ends of the other pickets, means for bend-
ing the shorter pickets substantially at their
medial line, means for moving the bent ends
of the shorter pickets out of the path of the 115
feeding longer pickets, means for twisting
the line wires for interweaving the pickets
therewith, means for moving the line wires
and, interwoven pickets for regulating the
space between the pickets, means for sepa- 120
rating the line wires when the picket form-
ing wire is being fed therebetween, and
means for tensioning the line wires for caus-
ing uniform twists between the line wires.

22. In a fence loom, means for feeding a 125
strand of wire between pairs of line wires,
means for cutting the strand of wire into
lengths for forming pickets, means for de-
termining the length of said pickets, a pawl
and ratchet mechanism for controlling the 130

- picket feeding mechanism, and a cam for releasing said pawl from the ratchet mechanism for stopping the feeding mechanism a prescribed interval and omitting the feeding of one picket between the line wires.
23. In a fence loom, means for feeding a strand of wire lengthwise between pairs of line wires, means for cutting said strand of wire into lengths for forming pickets, a bending head for bending the ends of certain of the pickets, formers on said head, a bending pin for forcing the end of the picket around said formers for shaping the same, means for intermittently moving the bending pin in a circular path, means for holding the bending pin against movement at prescribed intervals, and means for elevating said head for positioning the bending pin in the path of the end of the picket to be bent.
24. In a fence loom, means for feeding a strand of wire lengthwise between pairs of line wires, means for cutting said strand of wire into lengths for forming pickets, a bending head for bending the ends of certain of the pickets, formers on said head, a bending pin for forcing the end of the picket around said formers for shaping the same, means for intermittently moving the bending pin in a circular path, means for holding the bending pin against movement at prescribed intervals, means for elevating said head for positioning the bending pin in the path of the end of the picket to be bent, and means on the head for elevating the picket forwardly of the bending picket whereby the bending end and the bending pin will pass below the forward picket.
25. In a fence loom, means for feeding a strand of wire between pairs of line wires, means for severing said strand of wire into lengths for forming pickets, means for forming said pickets of different lengths, means for bending certain of said pickets substantially in half, comprising an anvil, a bending pin, means for rotating said bending pin for engaging the picket to be bent and for moving the bending portion substantially at right angles to the remaining portion of the picket, means for operating said bending pin, means for raising and lowering said anvil, a bending head, formers on said bending head, means for raising and lowering said bending head, a second bending pin, means for elevating the bending head and second bending pin to position them to engage and complete the bending operation of the picket, means for intermittently operating the second bending pin, and means for holding said second bending pin in operative position at intervals.
26. In a fence loom, means for feeding a single strand of wire lengthwise between a plurality of pairs of line wires, twisting members formed in sections for simultaneously twisting all the pairs of line wires, means for severing the strand of wire into lengths for forming pickets, means for bending certain of said pickets substantially at their longitudinal centers and disposing said bending end parallel with the line wires during a partial twisting operation, means for feeding an additional picket between the line wires while the bending end of the preceding picket is still parallel with the line wires, means for omitting the feeding of a picket, and means for positioning the bending end of the picket between the line wires and in position to occupy the space of the omitted picket.
27. In a fence loom, automatic means for crimping and feeding an endless strand of wire lengthwise between a plurality of pairs of line wires, sectional twisters through which said line wires project, automatic means for operating said twisters for forming twists in said line wires, automatically operated means associated with said feeding means for forming bends in the strand of wire after said strand of wire is positioned between the line wires, means for severing the strand of wire into lengths for forming pickets subsequent to partially weaving the pickets between the line wires, and automatically operated means for lifting vertically certain of the sections of the twisters for spacing the line wires to receive the strand of wire.
28. In a fence loom, means for automatically feeding an endless strand of wire between a plurality of line wires, automatic means for severing the strand of wire into lengths for forming pickets subsequent to the feeding of the strand of wire between the line wires, a plurality of twisters for twisting said line wires for interweaving the pickets therebetween, longitudinally movable means for rotating said twisters simultaneously and in unison, means for directing a series of intermittent thrusts against the twister operating means while moving in one direction, and automatically operated means for reversing the movement of the twister operating mechanism.
29. In a fence loom, means for twisting line wires for incorporating pickets therebetween, longitudinally movable means for simultaneously and uniformly operating said twister means, oscillating means adjacent each end of the twister operating means for directing thrusts there against for moving the operating means lengthwise, and automatically operated means for associating one of the thrust directing elements with the twister operating means and disassociating the other thrust directing element from the twister operating means.

In testimony whereof I hereto affix my signature.

CARL A. PORATH.
